MAX A. BUCH, OF DETROIT, MICHIGAN.

TACKING-STRIP FOR UPHOLSTERING.

1,188,407.

Specification of Letters Patent. Patented June 27, 1916.

Application filed November 15, 1915. Serial No. 61,492.

To all whom it may concern:

Be it known that I, MAX A. BUCH, a subject of the Emperor of Germany, residing at Detroit, county of Wayne, State of Michigan, have invented a certain new and useful Improvement in Tacking-Strips for Upholstering, and declare the following to be a full, clear, and exact description of the same, such as will enable others skilled in the art to which it pertains to make and use the same, reference being had to the accompanying drawings, which form a part of this specification.

This invention relates to tacking strips for upholstering, especially to a tacking strip of such flexible character that it can be readily bent to conform to the curvature of the body.

In the drawings, Figure 1 is a vertical section of a seat-back showing the upholstering in place. Fig. 2 is a vertical sectional detail showing how the parts go together. Fig. 3 is a vertical sectional detail showing the tacking strip attached to the upholstering. Fig. 4 is an elevational detail of the tacking strip. Fig. 5 is a vertical sectional detail of a modified form of tacking strip.

The body metal is designated *a* and is turned over at the top and then down to form a rounded surface for the seat-back at the top. For convenience of reference, this portion that is turned over and downward will be termed the large incomplete bead. Along the top of the upholstering *b* is secured a tacking strip *c*, which comprises a fiber strip thin enough to be flexible. The advantage of the use of this fiber strip is that the front covering and the backing of the cushion may be tacked to this strip before the upholstering is put into the job.

In fact, the tacking may preferably be done in the tufting mold, which is quite an advantage as when the cushion comes from the mold it is all ready to put into the job.

Preferably I employ with this fiber tacking strip *c* a thin metal channel strip *d* which acts as a carrier for the fiber strip and also serves as a clenching strip in the manner shown in Fig. 3, turning the points of the tacks back. After the fiber strip has been secured to the front covering and the backing of the cushion this strip may be secured to the downwardly-extending flange *e* of the large incomplete bead by means of the bolts and nuts *f* (Fig. 1). The great advantage of this tacking strip over the wooden strips

that have been used for similar purposes is that it is very pliable and hence easily conforms itself to the shape of the body portion to which it is attached, in this instance, the downwardly-extending flange *e*. Where wood is used, it is extremely hard to shape this substance to the exact curvature required. It will be noted that a strip *g* is inserted between the upholstering and the downwardly-extending flange *e* to complete the joint in the manner shown in Fig. 1. With an upholstering job done in the fashion shown and described, all the fastening devices are completely concealed as the bolt heads and nuts are all on the inside as will be seen in Fig. 1. This makes a very neat and at the same time a good job.

What I claim is:

1. A tacking strip for upholstering cushions, comprising a pliable metal channel strip in which is carried a strip of thin, pliable and penetrable material, the said strips being readily conformable to the shape of the member to which they are secured.

2. A tacking strip for upholstering cushions, comprising a pliable thin metal channel strip and a pliable fiber strip carried in the same to act as a tacking strip, whereby the tacking strip is readily conformable to the member to which it is secured.

3. In combination with a seat-back portion of a body, of an upholstering cushion, a fiber tacking strip to which the upholstering cushion covering and backing is tacked, said fiber strip being pliable and adapted to conform itself to the curvature of the body, and means for securing the fiber strip to the body portion forming the seat-back.

4. In a vehicle body, the combination of a body portion turned in and downward to form a large incomplete bead having a downwardly-extending flange portion, an upholstering cushion provided with a covering and backing, a thin pliable strip of penetrable tacking material to which the covering and the backing is tacked, and means for securing the said strip to the downwardly-extending flange portion of the large incomplete bead.

5. In a vehicle body, the combination of a body portion forming a part of the seat-back having the metal turned inwardly and downwardly to form a large incomplete bead provided with a downwardly-extend-

- ing flange portion, a seat-back cushion provided with a covering and backing, a tacking strip comprising a pliable metal channel strip infolding a pliable strip of penetrable material to which the covering and the backing of the cushion is tacked, and means for securing the said tacking strip to the downwardly-extending flange of the said large incomplete bead.
10. 6. In a vehicle body, the combination of a body portion forming a part of the seat-back, the said metal being turned inwardly and downwardly to form a large incomplete bead having a downwardly-extending flange portion, a seat-back cushion provided with a covering and backing, a tacking strip comprising a pliable channel strip of metal infolding a thin fiber strip, and bolts
- 5 and nuts for securing the said tacking strip to the downwardly-extending flange of the 20 large incomplete bead.
7. In combination with a seat-back portion of a body having a curvature, of an upholstering cushion, a tacking strip to which the upholstering cushion, covering 25 and backing is tacked, said tacking strip comprising a pliable channeled metal strip carrying a fiber strip arranged to conform itself to the curvature of the body when the same is put into the body, and means 30 for securing the tacking strip to the body portion forming the seat back.

In testimony whereof, I sign this specification.

MAX A. BUCH.
